CLAIM

The ornamental design for a cabinet scraper, as shown.

DESCRIPTION

FIG. 1 is a front, top, right side isometric perspective view of a first embodiment of cabinet scraper in accordance with my design;

FIG. 2 is a front elevation view of cabinet scraper as shown in FIG. 1;

FIG. 3 is a rear elevation view of cabinet scraper as shown in FIG. 1;

FIG. 4 is a left side elevation view of cabinet scraper as shown in FIG. 1;

FIG. 5 is a right side elevation view of cabinet scraper as shown in FIG. 1;

FIG. 6 is a top plan view of cabinet scraper as shown in FIG. 1;

FIG. 7 is a bottom plan view of cabinet scraper as shown in FIG. 1;

FIG. 8 is a front, top, right side isometric perspective view of a second embodiment of cabinet scraper in accordance with my design;

FIG. 9 is a front elevation view of cabinet scraper as shown in FIG. 8;

FIG. 10 is a rear elevation view of cabinet scraper as shown in FIG. 8;

FIG. 11 is a left side elevation view of cabinet scraper as shown in FIG. 8;

FIG. 12 is a right side elevation view of cabinet scraper as shown in FIG. 8;

FIG. 13 is a top plan view of cabinet scraper as shown in FIG. 8; and,

FIG. 14 is a bottom plan view of cabinet scraper as shown in FIG. 8.

The broken lines illustrate portions of the cabinet scraper which form no part of the claimed design.

The claimed design is shown with a symbolic break in its length. The appearance of any portion of the article between the break lines forms no part of the claimed design.

1 Claim, 8 Drawing Sheets
